NEGATIVE FEEDBACK AMPLIFIER CIRCUIT

Edmond Egbertus Carpentier, Eindhoven, Netherlands, assignor, by-mesne assignments, to Hartford National Bank and Trust Company, Hartford, Conn., as trustee

Application April 27, 1946, Serial No. 665,393
In the Netherlands September 25, 1942

Section 1, Public Law 690, August 8, 1946
Patent expires September 25, 1962.

2 Claims. (Cl. 179—171)

1

This invention relates to an amplifying circuit arrangement in which, for the purpose of decreasing the distortion which occurs in the circuit, use is made of negative feed-back, comprising an amplifying tube whose input circuit has supplied to it the voltage to be amplified, and whose anode circuit and cathode circuit each include an impedance, preferably a resistance, which impedances are connected to the input circuits of two push-pull connected amplifying tubes in such manner that the voltages set up at the said impedances control these tubes in push-pull, the amplified output voltage being taken off from the output circuit of these tubes. By the term "cathode circuit" we mean in this case the common part of the anode circuit and of the grid circuit.

A circuit arrangement of this kind is shown in Fig. 1 of the accompanying drawing. The circuit arrangement shown in this figure comprises an amplifying tube 1 whose control grid has a voltage to be amplified, supplied to it via input terminals 2 and 3 and whose anode circuit and cathode circuit include resistances 4 and 5 respectively of equal value. The anode and the cathode of tube 1 are connected in the usual manner to the control grids of two push-pull connected amplifying tubes 15 and 17 respectively via coupling condensers 7 and 9 and leakage resistance 11 and 13 respectively, due to which on controlling tube 1 the voltages set up at the resistances 4 and 5 control the tubes 15 and 17 in push-pull. The anode circuits of these two tubes include the primary winding 21 of an ordinary push-pull transformer 19, which transformer comprises, in addition, a secondary winding 23 from which an amplified output oscillation is derived.

Tube 1 is connected in accordance with the so-called "cathodyne arrangement," with the aid of which an alternating voltage asymmetrical relatively to ground is converted into a symmetrical voltage. A known property of this circuit consists in the whole voltage set up at the cathode resistance being supplied to the control grid of the amplifying tube in anti-phase with the input voltage to be amplified, in other words tube 1 has negative feed-back, resulting in an appreciable decrease of the distortion which occurs in this tube. Another consequence of the negative feed-back coupling is, however, that the voltage set up at the cathode resistance 5 can at most become equal to the input voltage, in other words an amplified voltage is not set up at this resistance. In addition, in view of the push-pull

2

the anode resistance 4 must have a value equal to that of the cathode resistance 5, so that only a voltage equal to the input voltage is set up also at the anode resistance and hence the total voltage amplification only amounts to 2:1. The drawback of this small amplification is only offset by tube 1 having negative feed-back; the tubes 15 and 17 are not provided with negative feed-back, so that the distortion that occurs in these tubes is not decreased.

An object of the invention is to provide an improvement of the circuit arrangement to which the invention has reference, whereby negative feedback is incorporated in the circuit under conditions unchanged as regards amplification the tubes 15 and 17.

According to the invention, this improvement consists in a negative feedback voltage or current derived from the output circuit of the push-pull connected tubes being supplied to the cathode circuit of the first-mentioned amplifying tube and the cathode impedance of this tube being given a lower value than the anode impedance.

The invention will be set out more fully by reference to the accompanying drawing showing, by way of example, one form of construction of a circuit arrangement according to the invention.

The circuit according to the invention shown in Fig. 2 substantially corresponds with that of Fig. 1 and is provided with corresponding reference numerals. The difference with Fig. 1 consists in that in the circuit shown in Fig. 2 a negative feed-back voltage derived from the anode circuit of the tube 15 is supplied to the cathode resistance 5 of tube 1 via a blocking condenser 25 and a resistance 27. This negative feed-back voltage as well as the voltage set up at the cathode resistance 5 and a result of the control of tube 1 are in anti-phase with the input voltage of tube 1; the two first-mentioned voltages are consequently in phase and support each other, that is to say the anode current of tube 1 flowing through the resistance 5 is increased by the negative feed-back current flowing through the resistance 27. Consequently, the voltage drop at the resistance 5 required for the push-pull control of tube 17 is obtained at a lower value of this resistance than in the circuit shown in Fig. 1, that is to say that in the circuit according to the invention the cathode resistance 5 of tube 1 must be smaller than the anode resistance 4.

In the circuit shown in Fig. 2 the portion of the output voltage of tube 1 which is thus fed back to the input circuit of this tube is smaller than in the circuit of Fig. 1, but on the other

hand a portion of the output voltage of tubes 15 and 17 is also fed back to the said input circuit, so that unlike Fig. 1 these tubes have also negative feed-back. This result is achieved with the circuit arrangement according to the invention without any decrease in amplification of tube 1 relatively to the circuit of Fig. 1. In fact, the anode resistance 4 can remain unchanged, while in spite of the lower value of the cathode resistance 5 again as great a voltage is set up at this resistance as at the resistance 4, so that the voltage amplification of tube 1 in the circuit shown in Fig. 2 is also 2:1.

What I claim is:

1. An amplifier circuit arrangement comprising a first electron discharge tube having a cathode, a grid and an anode, an anode impedance element coupled to said anode, a cathode impedance element having an impedance value smaller than that of said anode impedance element and being coupled to said cathode, means to apply signals to be amplified to the grid of said first tube to produce a first output voltage across said anode impedance element and a second output voltage across said cathode impedance element in anti-phase with respect to said first output voltage, a second and a third electron discharge tube each having a cathode, a grid and an anode and being connected in pushpull amplifying relationship, means to couple the grid of said second tube to the anode of said first tube to apply said first output voltage thereto, means to couple the grid of said third tube to the cathode of said first tube to apply said second voltage output thereto, and means to couple the anode of said second tube to the cathode of said first tube to connect said first and said push-pull connected tubes in negative feedback relationship thereby to produce an output sig-

nal substantially proportional to said applied signals.

2. An amplifier circuit arrangement comprising a first electron discharge tube having a cathode, a grid and an anode, an anode resistor coupled to said anode, a cathode resistor having a resistance value smaller than that of said anode resistor and being coupled to said cathode, means to apply signals to be amplified between the grid and cathode of said first tube to produce a first output voltage across said anode resistor and a second output voltage across said cathode resistor in anti-phase with respect to said first output voltage, a second and a third electron discharge tube each having a cathode, a grid and an anode and being connected in pushpull amplifying relationship, means to couple the grid of said second tube to the anode of said first tube to apply said first output voltage thereto, means to couple the grid of said third tube to the cathode of said first tube to apply said second voltage output thereto, and means comprising a resistor coupling the anode of said second tube to the cathode of said first tube to connect said first and said pushpull connected tubes in negative feedback relationship thereby to produce an output signal substantially proportional to said applied signals.
